UNITED STATES PATENT OFFICE.

ROBERT ASHE, OF SOMERVILLE, MASSACHUSETTS.

EDGE-BURNISHING MACHINE.

SPECIFICATION forming part of Letters Patent No. 313,155, dated March 3, 1885.

Application filed October 27, 1884. (No model.)

To all whom it may concern:

Be it known that I, ROBERT ASHE, of Somerville, in the county of Middlesex and State of Massachusetts, have invented a new and useful Improvement in Edge-Burnishing Machines, which will, in connection with the accompanying drawings, be hereinafter fully described, and specifically defined in the appended claims.

10 This invention has for its object certain improvements in that class of edge-burnishing machines wherein the rubbing-tool is rapidly vibrated to a limited extent while in contact with the surface to be burnished, and it will be hereinafter more particularly described and claimed.

15 In the accompanying drawings, Figure 1 is a side elevation of a machine embodying my invention. Fig. 2 is a top or plan view of that portion of Fig. 1 shown at the left hand of the driving-pulley. Fig. 3 is an elevation taken at the left of Figs. 1 and 2. Fig. 4 is a horizontal section taken on line $x-x$, Fig. 1. Fig. 5 is a horizontal section taken as on line 25 $W-W$, Fig. 3.

20 In said views, A represents the frame adapted to receive and support the operative parts, and to be secured to a stand, bench, or other suitable support. A short arbor, a , is journaled in the bearings b of said frame, a driving-pulley, c , being secured on said arbor, as also the hand or balance wheel d , said wheel being secured in place by nut e , and the arbor being held from lineal displacement by said 25 nut and the collar f . Two pitmen, g g' , are mounted on wrist-pins j j' of arbor a ; and at their outer ends are respectively pivoted on wrist-pins h h' of arms i i' , said arm i being rigidly secured on the inner end of rock-shaft k , while arm i' is secured by set-screw t to the short arm s of collar p , which is loosely mounted on said rock-shaft k between the journal-bearings l l' of said arbor, said bearing l' being united to frame A by rib m .

30 40 Upon the front end of rock-shaft k I secure the fore-part iron u , whose end v is the counterpart of the surface to be burnished, and I secure to the curved depending arm 2 of sleeve p , by a pivotal connection, y , the shank-iron w , whose end face, x , is of the desired 45 form. The upper end of said iron w is adjust-

ably secured by set-screw z to said arm 2, so that the lower end of w may be adjusted in its relation to iron u . A finger-rest, 3, is pivotally secured at 4 to the outer journal-bearing, 55 l' , and is adjustably secured by set-screw 5 to said bearing l' , so that it may be adjusted in its relative proximity to irons u and w . Said finger-rest, in its lower portion, is formed trough-like to receive or overlie iron w , and 60 is of a width to allow the requisite limited lateral vibration of the iron w .

The wrist-pins j j' are clearly shown in Fig. 5, being arranged with their axes out of line with the axis of arbor a , and so that they constitute cranks arranged at one hundred and eighty degrees relatively to each other—that is, are exactly opposite each other—therefore when arbor a is rotated by a belt on its pulley c the arms i i' will simultaneously approach and recede from each other, and hence the irons u w will be vibrated in opposite directions, they being shown in Fig. 3 as at their extreme movement in one direction and when arms i i' are at their greatest remove from 75 each other, while the next half-revolution of arbor a would reverse the relative positions of said arms i i' and irons u w , such movement resulting from the described throws of wrist-pins j j' and arms i i' , rock-shaft k , and loose 80 sleeve p , to which said arms are respectively secured, which shaft and sleeve respectively perform the functions of rock-shafts by imparting to irons u and w their described vibratory movement.

85 By thus arranging two burnishing-tools adapted to vibrate in opposite directions the usual tremor or vibration resulting from the rapid reciprocation of a single iron is avoided, thereby effecting a better finish of the edge, 90 as the less tremor of the machine the more perfectly can the work be performed; besides the paralyzing effect of such tremor upon the hands and arms of the operator is avoided. Besides this, the time required for reversing 95 a double-ended iron is saved, as both my irons are always ready for use, and it is only necessary to change the shoe-edge from one to the other.

The advantages of the described adjustment 100 of iron w and rest 3 relatively to iron u are obvious, and need not be described.

I am aware that two vibrating irons have been heretofore employed in a burnishing-machine; but they were arranged to vibrate in the same plane, instead of being in different planes—that is, one behind the other—and were adapted to act simultaneously upon the edge, and hence extended a greater distance along the shoe-edge than mine do, and therefore in working upon those parts of the edge which curve vertically, or relatively to the plane of the sole, such irons tended to cross the line of the sole next the upper, and hence to mar and injure the same.

In practice I prefer to give to wrist-pin j three-sixteenths ($\frac{3}{16}$) of an inch throw, and to wrist-pin j' one-half that amount of throw, and hence iron w , by its greater length, will have about two-thirds the vibratory action of iron u , which is requisite by reason of the greater vertical curve at the shank of the shoe than at the fore part, and the consequent tendency of the shank-iron to cross the curved line (next the upper) of the sole edge when the iron vibrates, as it does, in a right line.

I claim as my invention—

1. In an edge-burnishing machine, the combination of a finger-rest and two burnishing-irons arranged to simultaneously vibrate in opposite directions, but singly operative, in planes one behind the other, and each formed with an operative face adapted to burnish a portion of the sole unlike the other, and each constantly in position to co-operate at the will of the operator with said rest, whereby either of said tools may at will be conjointly employed with said rest without adjustment in relation thereto, substantially as specified.

2. In a burnishing-machine, two burnishing-irons arranged to simultaneously vibrate in opposite directions, but singly operative, in planes one behind the other, combined with means, substantially as described, to adjust

one of said irons toward or from the other, whereby its plane of vibration may be varied relatively to that of the other, substantially as specified.

3. In an edge-burnishing machine, the combination of two burnishing-tools arranged to simultaneously vibrate in opposite directions, but singly operative, in planes one behind the other, and a finger-rest in permanent co-operative relation to both, one of said tools and said rest being capable of adjustment toward or from the other tool, substantially as specified.

4. In an edge-burnishing machine, two burnishing-tools formed with different operative faces, each adapted to burnish a portion of the sole unlike the other, and arranged to simultaneously vibrate in opposite directions, but singly operative, in planes one behind the other, combined with means, substantially as described, to impart to said tools a differentiated extent of vibratory movement, substantially as specified.

5. In an edge-burnishing machine, the combination of two burnishing-irons arranged to simultaneously vibrate in opposite directions, but singly operative, in planes one behind the other, and each formed with an operative face adapted to burnish a portion of the sole unlike the other, and each constantly in position for use at the selection of the operator, substantially as specified.

6. In an edge-burnishing machine, the combination of arbor a , having the crank-like wrist-pins j j' , pitmen g g' , arms i i' , rock-shaft k , and sleeve p , burnishing-irons u w , and finger-rest 3, all combined to operate substantially as specified.

ROBERT ASHE.
